US00D579670S

(12) United States Design Patent
Buziol et al.

(10) Patent No.: US D579,670 S
(45) Date of Patent: * Nov. 4, 2008

(54) DECORATIVE PATCH FOR CLOTHING

(75) Inventors: Claudio Buziol, deceased, late of Montebelluna (IT); by Paola Dametto, legal representative, Montebelluna (IT); Gian Paolo Buziol, Montebelluna (IT); Silvia Buziol, Montebelluna (IT)

(73) Assignee: Fashion Box International S.A., Luxembourg (LU)

() Term: 14 Years

(21) Appl. No.: 29/227,341

(22) Filed: Apr. 5, 2005

(30) Foreign Application Priority Data

Oct. 13, 2004 (EM) 000240965

(51) LOC (8) Cl. 05-03

(52) U.S. Cl. D5/63

(58) Field of Classification Search ..... D5/1-3, D5/5, 7, 8, 11, 13-16, 19, 20, 23-28, 30, D5/32, 35-37, 39, 43, 45, 47, 49, 50, 52-66, D5/99; D2/742, 749, 994; D6/582, 583, D6/595, 596, 598, 603-606, 608, 613-616, D6/617, 619, 622; D7/396.4, 396.5; D24/124-126; D25/142, 152; 5/413 AM, 709; 156/148, 156/209; 162/134, 140, 231; 428/17, 18, 428/151, 154, 156, 171, 187, 198, 199, 540, 428/542.2, 542.6, 919, 904.4; D1/125, 126, D1/128; 2/244, 275
